F. C. LEE.
SUSPENDERS.
FILED MAR. 11, 1922.

FIG. 1.

FIG. 2.

INVENTOR
FREDERICK C. LEE

BY
Frederick C. Lee

ATTYS.

UNITED STATES PATENT OFFICE.

FREDERICK CHARLES LEE, OF TORONTO, ONTARIO, CANADA.

SUSPENDERS.

Application filed March 11, 1922. Serial No. 543,019.

To all whom it may concern:

Be it known that I, FREDERICK CHARLES LEE, a subject of the King of Great Britain, and a resident of the city of Toronto, in the county of York, in the Province of Ontario, Canada, have invented certain new and useful Improvements in Suspenders, of which the following is the specification.

My invention relates to improvements in suspenders and the object of the invention is to devise a suspender of the type comprising loop-like shoulder straps extending around the shoulders and a detachable connection at the lower end for connecting the loop to the trousers of the wearer and a cross back connection between the loops at each side of the back and the object of my invention is to provide a connection between the loop members and the cross strap and between the upper and lower portions of the loop as will permit of a free flexible movement to conform with the movements of the body and also permit of the ready adjustment of the loops in accordance with the height of the wearer so that the cross back connection will be in proper position and it consists essentially of the arrangement and construction of parts as herein-after more particularly explained.

Fig. 1 is a perspective view of my suspender showing its application.

Fig. 2 is an enlarged perspective detail of fragmentary portions of the suspender showing the connection between the upper and lower portions of the loop and the cross connection.

In the drawings like characters of reference indicate corresponding parts in each figure.

1 and 2 indicate loop members formed of resilient fabric and extending around the shoulders of the wearer, the lower portion of the loop being connected in the usual manner by a wire tab 3, the front portion 4 of the loop passing downward through the tab 3 and then upward.

The forward portion of each loop extends upward through a buckle 4 in front of the centre cross bar 4^x thereof and behind the top and bottom cross bars of the buckle as clearly indicated in Fig. 2. 5 is a triangular loop connector. A connector 5 is located over each shoulder blade of the wearer with

their adjacent sides set substantially vertical.

The lower end of the back portion of the loop 1 extends upward and passes around the portion 5^z of the triangular loop 5, the free end being connected to the major portion thereof by a line of stitching 6. The forward portion of the loop 1 as before described extends through the buckle 4 and passes upward therefrom in front of and over the shoulder of the wearer and then downward and around the portion 5^z of the loop 5 then returning upward again over the shoulder and downward in front of the shoulder of the wearer and is passed in front of the cross bar 4^x of the buckle 4, the free end being carried inward and upward and connected by a line of stitching 7 to the major portion of the loop. The portion 5^x of the triangular loop connector 5 is enlarged at 8 and provided with a vertically disposed slot 8^x. 9 is a cross connection formed by a band of elastic material secured at one end by passing through the slot 8^x of one of the loops 5 being secured by a line of stitching. The opposite end of the band passes freely through the corresponding slot 8^x of the other triangular loop and then passes towards the centre of the back of the wearer. 11 is a buckle similar to the buckle 4 provided with a centre cross bar 11^x extending behind the major portion of the band 9. The free end of the band is connected to the centre cross bar of the loop as clearly indicated.

By this means it will be seen that the loops 1 and 2 may be easily adjusted, the forward portion of each loop slipping freely around the portion 5^z of the corresponding loop connector 5 throwing the loop to the proper position and at the same time the cross band may be easily adjusted so as to draw the loops 1 and 2 and the loop connectors 5 more or less close together. Also such a connection provides for a free flexible movement of the suspender so that it will readily conform to the movements of the wearer at all times.

It will also be seen that by my construction a straight and direct pull is exerted from the point of attachment to the trousers up to the back of the shoulder preventing any undue friction upon the back of the

wearer due to the movement of the wearer's body as is commonly the case rendering the suspender uncomfortable to wear and tending, particularly in hot weather, to produce sores.

What I claim as my invention is:

In a suspender, the combination with the tabs adapted to be detachably connected to the sides of a pair of trousers, a loop member divided into two portions extending upwardly from each tab, the rear portions of the loops converging towards the centre of the back of the wearer, front buckles through which the front portions of the loops extend in slidable frictional engagement with the buckle and over the shoulders of the wearer into proximity to the ends of the rear portions of the loops and return-

ing beneath themselves in loop form back over the shoulders to the buckles to which they are positively secured, a triangular open centered connector located over each shoulder blade of the wearer to one side of each of which one of the aforesaid rear loop portions is secured and around the opposite side of which the front portion of the loop freely extends, a cross connection securing the remaining or opposite sides of the triangular connectors, one end of such cross connection being secured to one of the triangular connectors and looped freely around the opposing side of the other triangular connector, and a buckle for frictionally engaging the free end of the cross connector to the main portion thereof.

FREDERICK CHARLES LEE.
